(57) **CLAIM**

The ornamental design for a wheel mount, as shown and described.

DESCRIPTION

FIG. 1 is a side perspective view of the wheel mount showing our new design;

FIG. 2 is a side elevational view thereof, the opposite side being hidden in use and forming no part of the claimed design;

FIG. 3 is a rear elevational view thereof;

FIG. 4 is a front elevational view thereof;

FIG. 5 is a top plan view thereof; and,

FIG. 6 is a bottom plan view.

The broken lines define a piece of luggage and a wheel to which the wheel mount can be attached and form no part of the claimed design.

1 Claim, 5 Drawing Sheets
